UNITED STATES PATENT OFFICE

JACOB NESSLY PORTER, OF NEWELL, WEST VIRGINIA, ASSIGNOR TO THE GLOBE BRICK COMPANY, OF EAST LIVERPOOL, OHIO, A CORPORATION OF WEST VIRGINIA

MACHINE FOR MAKING PAVING BRICK

Application filed November 12, 1927. Serial No. 232,866.

This invention relates to brick making machines, and particularly to such machines adapted to form spacing lugs on bricks for paving purposes.

The features of my invention consists in the improvements hereinafter described and illustrated, wherein a column of clay is caused to flow continuously from the forming die of the forcing machine, having several ribs raised up on one surface of said moving column.

Also in providing a roller provided with transverse ribs which are adapted to form transverse grooves in said die formed ribs, so that when said bricks are laid in a pavement, and a fluid filler is poured into the crevice between said brick, said fluid filler can flow through said transverse grooves pressed into said die formed ribs and completely fill all the voids between the paving bricks.

These and other features of my invention will appear hereinafter, and are illustrated in the accompanying drawings as follows, viz: Figure 1 is a side view in elevation of a portion of a brick making machine embodying my invention.

Figure 2 is a transverse section of the same on the line 2—2 in Fig. 1.

Figure 3 is a view similar to Fig. 1 of the same on an enlarged scale, with a portion broken away.

Figure 4 is a transverse section of the same on the line 4—4 in Fig. 3.

Figure 5 is a plan view of the clay column as it is formed by the forming die, and by the ribbed roller of my invention.

Figure 6 is a transverse section of the clay column on the line 6—6 in Fig. 3.

Figure 7 is a right hand view of a portion of Figure 5.

Figure 8 is a plan view of a brick cut from a clay column.

The wire cutting machine by which the column of clay is divided into bricks is not shown, as the same is old and well known and forms no part of the present invention.

In these drawings A indicates the forming die of a forcing machine which forms the clay

column into proper shape so that bricks can be cut therefrom as shown in Fig. 8.

B indicates the frame upon which the measuring belt B' is mounted and which belt supports the column of clay C, on its way to the wire cutting machine, not showing. Secured to the frame B, B, are uprights C' C', in which a pivot rod D is mounted. Secured on the pivot rod D are the side bars D' of the frame in which a roller E is secured. The side bars D' are provided with a cross bar F, see Fig. 2, and with a cross bar F' by means of which said side bars D' are maintained in rectangular form, so that the roller E will always be square with the column of clay C, and will roll on the column C as the same is forced forward from the die A.

In Fig. 6 the ribs G, G, G, are formed by the die A and extend longitudinally of the column C.

The roller E is provided with ribs E' which are of sufficient size that when pressed into the ribs G of the clay column will form transverse grooves g, see Figs. 5 and 7 therein, so that when the bricks have been dried and baked, they will have lugs H thereon, see Figs. 7 and 8.

The transverse cut surface shown in Fig. 6 will be laid up, with the lugs H on the die formed surface separating the bricks.

A cross bar J is secured to the uprights C' in which is placed a screw K which extends therethrough and engages the cross-bar F which prevents the end of the frame from raising the rod D in the opening c, so that by unscrewing the screw K so that the pivot rod D can be raised upward the frame D' and roller E can be removed from engagement with the uprights C' and removed bodily when desired.

In Fig. 3, the openings c in the uprights C' are elongated, and are provided with an opening c' to admit of the passage of the pivot rod therethrough, so that the frame and roller E can be removed, or replaced without removing said uprights C'. The axle e is secured to the side bars D' by means of U-shaped bolts e' or in any other suitable manner, so that said axle will not move laterally with reference to said side bars D'.

Having thus fully described the mechanism by means of which spacing lugs can be formed on the die formed surface of bricks, I do not desire to be limited to the exact construction shown and described as many modifications can be made therein without departing from the scope of my invention, therefore what I claim as new and desire to secure by Letters Patent is:

10. A machine for making paving brick, comprising a forming die having spaced slotted portions in its upper wall adapted to provide a clay column with spaced longitudinal ribs on its upper face, a traveling belt for receiving the clay columns, spaced standards at opposite sides of the belt having rearwardly opening shouldered sockets therein, a freely floating frame fitting at its forward end between the standards, a roller mounted in the 20 frame and having spaced transverse peripheral ribs adapted for embedding in said ribs of the clay column to form spaced pairs of spaced projections on the clay column, and a rod extending through the forward end of 25 the frame and extending therebeyond for engagement in said sockets of the standards for detachably and pivotally connecting the frame to the standards.

In testimony whereof I affix my signature.

JACOB NESSLY PORTER.
